Charles E. Gill

ATTORNEY

UNITED STATES PATENT OFFICE.

VICTOR GAERTNER, OF NEW YORK, N. Y., ASSIGNOR TO CONTINENTAL SHEFFIELD SILVER CO., OF BROOKLYN, NEW YORK, A FIRM.

DESIGN FOR AN ARTICLE OF HOLLOW TABLEWARE.

55,773.

Specification for Design.

Patented July 13, 1920.

Application filed February 20, 1920. Serial No. 360,171. Term of patent 14 years.

To all whom it may concern:

Be it known that I, VICTOR GAERTNER, a citizen of the United States, residing at New York city, in the county and State of New York, have invented a new, original, and ornamental Design for an Article of Hollow Tableware, of which the following is a specification, reference being had to the accompanying drawings, forming a part thereof, and in which—

I claim:

The ornamental design for an article of hollow tableware, as shown.

VICTOR GAERTNER.
